DEVICE FOR BRINGING THE STOCK STREAM
UPON THE SCREEN OF A PAPER MAKING
MACHINE

Wilhelm Thaler, Heidenheim-on-the-Brenz, Germany, assignor to American Voith Contact Co. Inc., New York, N. Y., a corporation of New York

Application March 10, 1938, Serial No. 195,035
In Germany January 25, 1937

1 Claim. (Cl. 92—44)

This invention relates to devices for bringing the stock stream upon the screen of a paper making machine.

The object of the invention is to provide means specially adapted to solve the problems attendant high speed stock impingement upon the screen.

The object is further to provide means enabling the stock stream to be varied in direction and in respect to the screen, and also to vary the point of impact of the stream upon the screen, in a manner to assure smoothness and quietness of the stream.

The object is further to provide simple means to vary the positions of the lips of the stock stream nozzles, the essential being that however the lips vary in respect to each other, the lower lip is within the upper lip.

With these objects in view, the invention in its simplest concept consists in having the upper portion of a stock inlet nozzle substantially horizontal or parallel with the upper surface of the screen of a Fourdrinier paper making machine, and the lower portion inclined in respect thereto, with the upper free discharge end at all times extending beyond the lower free discharge end, and the discharge opening of the nozzle placed approximately at the part of the front breast roll.

The invention consists further of combinations therewith, of means for adjustment, and, lastly, of a double nozzle, the outer walls of which are adjustable.

The invention further consists of certain features hereinafter to be described. The invention will be shown in the drawing in the forms of embodiments, and will be finally pointed out in the claim.

In the accompanying drawing—

Figure 1 is a vertical section of the fore part of a screen, the front breast roll, and the improved nozzle applied thereto.

Figure 2 is a similar section with the same known parts, but with another embodiment of the novel nozzle applied thereto.

Similar characters of reference indicate corresponding parts throughout the various views.

Referring to the drawing, and more particularly to Figures 1 and 2, the screen breast roll 8, and part of the Fourdrinier screen 9 is there shown.

50 In Figure 1, the stock supply channel 7 guides and feeds the stock to a nozzle 10. In Figure 2, the stock also enters the nozzle 11, in this embodiment, from a stock inlet box 12. The nozzle 11 is formed of a substantially horizontal wall 13 and of a wall 14 inclined thereto, the end of the

wall 13 extending beyond the end of the wall 14. In this embodiment, these walls 13 and 14 are fixed or stationary and are arranged in the relationship shown in Figure 2. Adjustments of the nozzle 11 may be made. For this purpose a 5 movable extension plate 15, which is also substantially horizontal or parallel with the horizontal portion of the screen 9, is supported by an adjusting device secured to the housing of the stock inlet box 12 at 16. The plate 15 has 10 a bent-up portion 17 provided with an opening to permit the passage of a screwthreaded bolt 18 secured at 16 to the box 12. At either side of the bent-up portion 17, screwthreaded nuts 19 and 20 are arranged. The proper rotation of the nuts 19 and 20 on the bolt 18, with the corresponding movement of the plate 15, enables the plate 15 to be moved horizontally, and then fixed into relatively permanent position. The plate 15 slides upon the upper plate 13 of the nozzle 11, and is, of course, in watertight connection therewith. By such adjustment means, not new per se, or by other suitable means, the plate 15 regulating the outflow of the upper portion of the nozzle 11, may be horizontally moved to and fro, and, as stated, placed into a relatively permanent position.

The lower plate or portion of the nozzle 11 is formed by the upwardly inclined member 14, which, as before stated, terminates inwardly of the end of the plate or portion 13. To the exterior of the portion 14, there is provided an adjustment means, similar in operation to the one just described. To the plate 14 is secured an upright plate 20, through which a bolt 21 35 passes, which is held in position by nuts 22 and 22a. The bolt 21 is screwthreaded and is engaged by two rotatable nuts 23 and 23a, between which a bent portion 24 of the plate 25 is held, the bent portion 24 being provided with an opening for the passage of the bolt 21. The free end of the plate 25 is below and within the free end of the plate 15. By the adjustment described, the plate 25 may be moved to and fro, but always within the limitation imposed, namely, to stay within the plate 25, as described. As the adjustment means per se are not novel, other suitable means well known may be used. By the adjustment shown in Figure 2, the stock flow 30 is 40 given a curved passage at 31, as shown in Figure 2.

The stock box 12 may also be raised or lowered by suitable means, or the breast roll 8 may be raised or lowered. By these various adjustments, 45 50 55

a variation in the direction of flow of the stock upon the screen, as also a variation in the position of impingement of the stock flow upon the screen, can be had, and the desirable ones selected.

In Figure 1, the invention is shown in a simpler embodiment. Here, a special form of stock flow channel 7 guides the stock along curved surface 33 substantially concentric with the curved surface 10 face 34, the curved surface 33 merging into a straight nozzle wall surface 14a, the free end of which terminates over the top but laterally of the same, of the breast roll 8. The curved surface 34 is fixed or stationary, relatively, and in cooperation therewith there is provided a plate 15a arranged substantially horizontal and parallel with the upper surface of the screen 9. This plate 15a has a downwardly bent portion 35, having an opening or space to enable the bolt 36 to pass therethrough. This bolt is fixed to a supporting member 37. Two rotatable nuts 38 and 38a are movable upon this bolt 36, and as moved determines the position of the plate 15a.

Again the adjustment means may be varied, as they are not new per se, and such variation is within the knowledge of the mechanic. Novel, however, is the relationship of the positions of the ends of the nozzle 10, in that whatever adjustment may be carried out from one nozzle portion to the other, or both in respect to each other, the upper plate or portion 15a is always beyond the lower plate or portion, as shown, for instance, in Figure 1, the free end of the upper plate or portion being approximately near the top of the breast roll, and in certain positions in substantial alignment with the vertical plane passing through the axis of the front breast roll. Again, other flexibilities may be provided, as, for example, if the channel 7 be made of a flexible 40 tubing, vertical lateral or inclined adjustments can be carried out in addition to the adjustment essential to the invention, that the lower portion of the nozzle be always within the upper portion, or that the upper portion always extend beyond the lower portion, in whatever position the respective portions may be. By this disposition of parts, the stock passes over the curvature of the breast roll due to the pressure of the stock, under a definite desired angle of impingement upon the upper screen of the paper making machine. A further advantage is that the invention lends itself especially to the utilization of higher working velocities machines, and that the stock flows with greater velocities upon the screen, the

stream being at the same time smoothed and quieted.

It has been seen that by means of the invention, the embodiments of which have been shown, the direction of the stock stream in respect to the screen, as also the position at which the stock stream strikes the screen, may be varied, by extremely simple means.

By the devices described it is possible to give the stock stream freely emerging from the nozzle various directions and to guide it so that it impinges or strikes the screen at different positions, beginning with approximately the top of the breast roll; also, the angle can be influenced, under which the impingement of the stock stream upon the breast roll may take place. All these positions of the stock stream are dependent upon the positioning of the upper portion or upperlip of the nozzle, in respect to the lower portion or lowerlip, the upper lip being parallel or approximately parallel with the screen, and movable substantially horizontally to and fro in respect thereto, and the under portion or underlip of the nozzle being positioned inclined in respect to the upper, and always within the upper. This projection of the upper lip portion has the further advantage that the stock stream moving at higher velocities upon the screen is smoothed and quieted.

It is obvious that various changes and modifications may be made in details of construction and the method of use of the above described embodiment of my invention without departing from the spirit thereof, such changes and modifications being restricted only by the scope of the following claim.

I claim:

In a nozzle device for a stock receiving container for bringing the stock stream upon the top of a horizontal screen passing over the breast roll of a paper making machine, in which the upper lip members of the nozzle are inclined to each other and in which the tip of the upper lip member extends beyond the tip of the lower lip member, the tips of both lip members being at the top of the breast roll, the combination of a horizontal upper lip member disposed parallel with the screen, an adjustable horizontal plate movable upon the upper lip member to and fro in a horizontal direction, and an adjustable plate movable upon the lower lip member parallel to the plane of the lower lip member, the tip of the plate on the lower lip member being at all times at a distance inwardly of the tip of the upper horizontal member plate.
